(57) **CLAIM**

The ornamental design for a wet/dry vacuum powerhead, as shown and described.

DESCRIPTION

FIG. 1 is an isometric front perspective view of a wet/dry vacuum powerhead in accordance with an embodiment of the present invention;

FIG. 2 is a front view thereof;

FIG. 3 is a back view thereof;

FIG. 4 is a side view thereof;

FIG. 5 is a side view, showing the side opposite that shown in FIG. 4;

FIG. 6 is a top view thereof; and,

FIG. 7 is a bottom view thereof.

The broken lines in the Figures are for the purpose of illustrating exemplary environmental structure and form no part of the claimed design.
